POWDER BOX ATTACHMENT

James L. Decker, Kenilworth, Ill., assignor to
Lovely Lady, Inc., Chicago, Ill., a corporation of
Illinois

Application June 28, 1937, Serial No. 150,682

6 Claims. (Cl. 132—82)

The present invention relates to attachments for powder boxes and more particularly to an attachment for converting the ordinary powder box into a vanity case.

5 The primary object of the invention is the provision of an inexpensive, simple, yet efficient device which may be attached to the ordinary powder box to convert the same into a vanity.

The device is so arranged as to prevent the 10 spilling of powder from the box and to permit use of a powder box in the purse.

For purposes of illustration there is shown in the accompanying drawing and hereinafter described a preferred embodiment of the invention. It is to be understood, however, that the 15 invention is susceptible of embodiment in various forms and is therefore not to be construed as limited to the precise device or arrangement shown, the true import and scope of the invention being defined by the appended claims.

Referring to the drawing:

Fig. 1 is a top plan view of the attachment; Fig. 2 is a bottom plan view;

Fig. 3 is a cross section taken on the lines 3—3 25 of Fig. 1;

Fig. 4 is a cross section showing the construction of the ordinary powder box;

Fig. 5 is a cross sectional view showing the attachment applied to the powder box of Fig. 4;

30 Fig. 6 is a section on the lines 6—6 of Fig. 5;

Fig. 7 is a view of the ordinary powder box with the top applied thereto; and

Fig. 8 is a top plan view showing the opening made in the closure material of the box 35 after the attachment has been applied.

Face powder is customarily sold in a box such as shown in Figs. 4 and 7 of the drawing. Referring to Fig. 4 it will be observed that the box comprises an outer casing indicated by the reference numeral 11, an inner ring 12, and a transparent closure material 13 which is stretched across the top of the box and is held in place by the ring 12.

In the use of such boxes the purchaser breaks 45 the closure material 13 in order to obtain access to the powder. The breaking of the closure 13 is a messy operation in that the powder tends to spill out. Furthermore, once the closure 13 is broken the powder is then loose in the box and each time that the cover of the box, which is shown in Fig. 7 by the reference character 14, is removed a certain amount of the powder is spilled.

It has been the practice of women to carry 50 such boxes of powder in their purse on various

occasions and when it is opened for use there is always the attendant messiness of removing the cover which permits the powder to spill and causes a cloud of it to rise in the air.

As shown in Figs. 1, 2, 3, 5 and 6 of the drawing the present invention relates to an attachment for powder boxes, the purpose of which is to obviate these and other difficulties. As it is apparent from Fig. 3 this attachment comprises a bottom member 15 which is provided with segmental flange portions 16 that project downwardly at the periphery of the bottom member 15. These downwardly projecting segmental flange portions 16 are preferably four in number. It is desirable that a continuous flange be 15 not used for reasons hereinafter set forth.

At the inner periphery of the bottom member 15 is a downwardly projecting flange member 17 provided with a serrated bottom edge 18. Hinged at one side of the bottom member 15 is a top portion 19 which is provided with a simple form of hinge 20. Opposite the hinge 20 in the top 19 is a catch member 21 which is adapted to hold the top 19 in engagement with the bottom member 15. As is apparent from 20 Figs. 3 and 5 of the drawing the bottom member 15 is provided with an annular groove 22 positioned immediately inside of the outer periphery of the bottom member.

Referring to Fig. 5 of the drawing it will be 30 seen that when the device is in use the downwardly projecting flanges 16 of the bottom member 15 are interposed between the inner ring 12 of the box and its outer side wall so that the attachment is firmly held in place. In view 35 of the fact that the downwardly projecting flanges 16 are not continuous the space between them permits the box to become slightly out of round so that there is an opportunity for a secure fit and any shrinkage or expansion that has taken place in the box is compensated for. This feature of the invention is of importance because no two boxes are of exactly the same diameter. If the downwardly projecting flange 16 were continuous, it is obvious that the box would have 40 45 to be exactly circular and of the same diameter as the flange portion, otherwise it would be difficult to insert the flange.

The serrated edge 18 of the downwardly projecting flange 17 cuts into the transparent covering material 13 so as to cut out a disk of the material in the center of the box as shown in Fig. 8.

In view of the fact that the device is inserted in the box with the cover 19 closed, there is no 55

escape of powder and the cover may be subsequently opened and the portion of the transparent material that has been cut out removed without disturbing the powder.

5 If desired, as shown in Fig. 5, a perforated metallic disk 23 may be inserted in the attachment, the purpose of this disk being to hold the powder in place and to permit only a small portion to sift through the perforations so that 10 when a powder puff is applied to the box only a small quantity of powder is disturbed and is available for use. The use of such a disk, however, may be dispensed with as the device is very effective without the same.

15 The annular groove 22 forms a sealing point at the edge of the box, as the transparent material 13 is forced up into the groove due to the compression of the powder when the attachment is inserted in the box.

20 In the use of the device it is only necessary for the user to open the cover and apply a powder puff to the powder. It will be found that the use of such an attachment dispenses the powder without spillage and makes the powder available 25 in a convenient form.

25 After the box of powder has been consumed it may be thrown away and the device attached to a fresh box of powder.

I claim:

30 1. A device of the class described including a bottom section adapted to fit into a powder box and a top section, a downwardly projecting flange portion at the outer periphery of the bottom section, said bottom section having an opening in the 35 central portion thereof, and a cutting flange projecting downwardly at the edge of said central opening.

2. A device of the class described including a bottom section adapted to fit into a powder box and a top section, said top section being hinged 40 to said bottom section, downwardly projecting

segmental flange portions at the outer periphery of said bottom section, said bottom section having an opening in the central portion thereof, and a cutting flange projecting downwardly at the edge of said central opening.

5 3. A device of the class described including a bottom section adapted to fit into a powder box and a top section, a downwardly projecting flange portion at the outer periphery of the bottom section, said bottom section having an opening in 10 the central portion thereof, and a flange having a serrated lower edge projecting downwardly at the edge of said central opening.

4. A device of the class described including a bottom section adapted to fit into a powder box 15 and a top section, a downwardly projecting segmental flange member at the outer periphery of the bottom section, said bottom section having an opening in the central portion thereof, and a serrated flange member projecting downwardly at 20 the edge of said central opening.

5. A device of the class described including a bottom section adapted to fit into a powder box and a top section, a downwardly projecting flange portion at the outer periphery of the bottom section, said bottom section having an opening in 25 the central portion thereof, a cutting flange projecting downwardly at the edge of said central opening, and a perforated disk positioned in said central opening.

6. A device of the class described including a bottom section adapted to fit into a powder box and a top section, a downwardly projecting flange portion at the outer periphery of the bottom section, said bottom section having an opening in 35 the central portion thereof, a cutting flange projecting downwardly at the edge of said central opening, and an annular groove positioned between said opening and the outer periphery of said bottom section.

JAMES L. DECKER.
